US00D917931S

(12) **United States Design Patent** (10) Patent No.: **US D917,931 S**
(45) Date of Patent: ** *May 4, 2021

(54) **AIR MATTRESSES**

(71) Applicant: **DBS-RAYMOND OUTDOOR & TOURISM BUSINESS INVESTMENT (UK) LIMITED**, Sheffield (GB)

(72) Inventors: **Fan Xiaolang**, Ningbo (CN); **Peng Shidong**, Ningbo (CN)

(*) Notice: This patent is subject to a terminal disclaimer.

(**) Term: **15 Years**

(21) Appl. No.: **35/504,924**

(22) Filed: **Apr. 20, 2018**

(80) **Hague Agreement Data**

Int. Filing Date: **Apr. 20, 2018**

Int. Reg. No.: **DM/100876**

Int. Reg. Date: **Apr. 20, 2018**

Int. Reg. Pub. Date: **May 11, 2018**
